DESIGN FOR A GLASS REFRIGERATOR DISH OR ARTICLE OF SIMILAR NATURE

Albert H. Nicholson, Columbus, Ohio, assignor to
The Federal Glass Company, Columbus, Ohio,
a corporation of Ohio

Application December 15, 1936, Serial No. 66,529

Term of patent 14 years

To all whom it may concern:

Be it known that I, Albert H. Nicholson, a citizen of the United States of America, residing at Columbus, in the county of Franklin and State of Ohio, have invented a new, original, and ornamental Design for a Glass Refrigerator Dish or Article of Similar Nature, of which the following is the specification, reference being had to the accompanying drawing, forming a part thereof:

Figure 1 is a perspective view of a glass refrigerator dish, showing my new design.

Figure 2 is a section taken substantially along line 2—2 of Figure 1.

Figure 3 is a section taken substantially along line 3—3 of Figure 2.

I claim:

The ornamental design for a glass refrigerator dish or article of similar nature, as shown.

ALBERT H. NICHOLSON.
